(75) Inventor: **Takeo Inagaki**, Tokyo (JP)

* cited by examiner

(73) Assignee: **Sony Corporation**, Tokyo (JP)

Primary Examiner—M. H. Tung
(74) Attorney, Agent, or Firm—Rader, Fishman & Grauer PLLC

(**) Term: **14 Years**

(21) Appl. No.: **29/149,322**

(57) **CLAIM**

(22) Filed: **Oct. 10, 2001**

The ornamental design for a computer generated image for display panel or screen, as shown and described.

(51) **LOC (7) Cl. 14-02**

DESCRIPTION

(52) **U.S. Cl. D14/486**

FIGURE is a front view of a computer generated image for display panel or screen showing my new design.

(58) **Field of Search** D14/485-95; D18/24-33;
D19/6; D21/324-33; D20/11; 345/700-726,
764-862

The broken line drawing of a display panel or screen is for illustrative purposes only and forms no part of the claimed design.
